(57) **CLAIM**

We claim the ornamental design for a bezel for a mobile device, as shown and described.

DESCRIPTION

FIG. 1 is a top plan view of a bezel for a mobile device showing our new design;

FIG. 2 is a bottom view thereof;

FIG. 3 is a front view thereof;

FIG. 4 is a side view thereof;

FIG. 5 is an opposite side view thereof;

FIG. 6 is a back view thereof;

FIG. 7 is a front perspective view thereof; and,

FIG. 8 is a rear perspective view thereof.

The broken lines shown in FIGS. 1-8 are included for illustrative purposes only and form no part of the claimed design.
